UNITED STATES PATENT OFFICE.

HARRY W. FAUBERT AND EDWARD E. WHEELOCK, OF WOONSOCKET, RHODE ISLAND.

DESIGN FOR A DENTURE BRUSH.

Application filed March 20, 1928. Serial No. 25,932. Term of patent 14 years.

To all whom it may concern:

Be it known that we, HARRY W. FAUBERT and EDWARD E. WHEELOCK, both citizens of the United States, both residing at Woonsocket, in the county of Providence and State of Rhode Island, have invented a new, original, and ornamental Design for a Denture Brush, of which the following is a specification.

Fig. 1 is a side view of a denture brush, showing our new design;

Figure 2 is a plan view of the back of the same; and

Fig. 3 is an end view, looking at the denture brush from the bristle end.

We claim:—

The ornamental design for a denture brush, as shown.

HARRY W. FAUBERT.
EDWARD E. WHEELOCK.
